UNITED STATES PATENT OFFICE.

PATRICK F. HIGGINS, OF FALL RIVER, MASSACHUSETTS.

LOOM-SHUTTLE.

1,141,186.

Specification of Letters Patent. Patented June 1, 1915.

Application filed June 17, 1913. Serial No. 774,102.

To all whom it may concern:

Be it known that I, PATRICK F. HIGGINS, a citizen of the United States, residing at Fall River, in the county of Bristol and 5 State of Massachusetts, have invented a new and useful Loom-Shuttle, of which the following is a specification.

This invention relates to improvements in loom-shuttles of the type designated as 10 "self-threading", and the object is to provide an improved shuttle of this character which may be quickly threaded and from which the thread will be positively prevented from escape during the operation of 15 the shuttle.

With the above object in view, the invention consists in the novel features of construction hereinafter fully described, particularly pointed out in the claims, and 20 clearly illustrated by the accompanying drawing, in which—

Figure 1 is a top-plan view of the thread-delivering end of a shuttle constructed in accordance with my invention; Fig. 2, a 25 side view of the same; Fig. 3, a transverse sectional view taken on the line A—B of Fig. 1; Fig. 4, a side-elevation of the eye-member of the shuttle, and Fig. 5, a bottom plan view.

30 I am aware that many different forms of shuttles of the type to which the present invention relates have heretofore been provided. Those in general use however, have a serious defect, namely, of permitting the escape of the thread and consequent unthreading of the shuttle. When the shuttle is in motion that portion of the thread between the bobbin and the eye has a tendency to what may be designated as "buckle" and lift, and following the same steps 35 or course by which it was threaded into the eye, disengage itself therefrom.

40 It is the purpose of my invention to so form and locate the eye that such unthreading is impossible.

The shuttle I have illustrated is a "right-hand" one, but the invention is equally applicable to a "left-hand" shuttle.

45 Referring now more particularly to the drawing, the numeral 1 designates the shuttle-body which is of the ordinary form. At the front-end thereof is a central recess 2, from one side-wall of which extends the curved threading-slot 3 which is disposed 50 downwardly from the top-surface of the shuttle-body and connects with a slot 4

formed in the side of the body and extending rearwardly to a transverse opening 5 located just in front of and in part below the bottom-wall 6 of the recess 2. Inserted 60 and secured by a pin or other suitable means in said opening 5, is the eye-member illustrated in detail in Figs. 4 and 5 of the drawing. The eye-member is shown in the form of a metal sleeve 7 having a diagonal 65 thread-inlet slot 8 extending longitudinally thereof from its outer end at a point below its center to its inner end at a point above its center where the metal is cut-away so that the sleeve at that end has its upper portion projecting beyond its lower portion as 70 at 9, and the lower edge of the projecting portion is a continuation of the upper wall of the slot. This lower edge of the projecting-portion 9 curves into the front-edge 10 75 of the latter, and the front-edge 10 continues into the lower edge 11 of said projecting-portion on the opposite or eye-side of the sleeve. The eye 12 is formed in this side of the projecting portion and has an 80 opening 13 at its bottom-side to permit ingress of the thread, and the lower-edge 11 of the projecting-portion of the sleeve curves downwardly and rearwardly to this ingress 13, forming a curved shoulder. 85 When in position in the shuttle-body, the ingress 13 to the eye 12 is located slightly below the bottom-wall 6 of the recess 2, and the opening 5 in which the sleeve is placed is somewhat larger in diameter than the sleeve 90 so that there is sufficient space for the thread to pass around the forward portion thereof from the slot 4 in order to enter the thread-inlet slot 8 of the eye-member.

95 In operation, the thread is inserted in the slot 3, from which it passes into the slot 4, and then around the forward side of the sleeve to the lowermost end of the thread-inlet slot 8. Entering this slot 8, it passes along the upper wall thereof and the lower edge of the projecting-portion 9 to and around the front-edge 10 of the latter and then down along the curved edge or shoulder 11 on the opposite side of the projecting-portion and the bottom-wall 6 of the 100 recess 2 to the ingress-opening 13 where it enters the eye 12.

105 From the above description, it will be seen that by reason of the shape of the eye and the curved edge or shoulder 11 as well as the location of the eye with respect to the wall 6 of the recess 2, and the location 110

and disposition of the thread-inlet slot 8, it is impossible for the thread to disengage the eye either by "buckling" or otherwise, and at the same time the shuttle is quickly and readily threaded.

Having thus fully described my invention what I claim as new and desire to secure by Letters Patent of the United States, is:

1. A loom-shuttle having a tubular eye-member placed transversely in the delivery-end thereof, said eye-member having an eye formed in one of its side-walls with an ingress-opening at its bottom side, and a thread-inlet slot in its opposite side-wall, said shuttle being formed with vertical and horizontal connecting threading-slots communicating with the thread-inlet slot of the eye-member.

2. A loom-shuttle having a tubular eye-member placed transversely in the delivery-end thereof, said eye-member having in its side-wall next the bobbin an eye open at its bottom, and a thread-inlet slot in its opposite side-wall inclined upward from the outer end of the eye-member, and a downwardly curved shoulder for conducting the thread from the slot to the opening of the eye, said shuttle being formed with vertical and horizontal connecting threading-slots communicating with the thread-inlet slot of the eye-member.

3. A loom-shuttle having a tubular eye-member placed transversely in the delivery-end thereof, said eye-member having in its side-wall next the bobbin an eye open at its bottom, and a thread-inlet slot in its opposite side-wall inclined upwardly from the outer end of the eye-member, said slot at the outer end of the eye-member being at substantially the bottom-side of said member, said shuttle being formed with vertical and horizontal connecting threading-slots communicating with the thread-inlet slot of the eye-member.

4. A loom-shuttle having an eye-member placed transversely in the delivery-end thereof, said eye-member formed with an eye open at its bottom, in combination with

a recess formed in the shuttle-body at the delivery-end thereof having its bottom-wall 50 above the openings to the eye, and threading-slots for leading the thread to said eye.

5. A loom-shuttle having a tubular eye-member placed transversely in the delivery-end thereof, said eye-member being cut 55 away at its inner end to form a projecting-portion extending from its upper side, an eye formed in the projecting-portion in the side next the bobbin having an opening at its bottom, a thread-inlet slot formed in the 60 eye-member extending upward from its outer end to the upwardly curved under edge of the projecting portion on that side of the eye-member, said curved edge continuing into the end-edge of the projecting- 65 portion and the end-edge into the under edge of the projecting-portion on the eye side of the eye-member which latter edge is curved downwardly and rearwardly to the opening of the eye, and vertical and horizontal 70 threading slots in the shuttle-body communicating with the thread-inlet slot of the eye-member.

6. A loom-shuttle having a tubular eye-member placed transversely in the delivery-end thereof, said eye-member having an eye open at its bottom formed near one end and in its side-wall next the bobbin, and an inclined thread-slot formed in its opposite side-wall, the portion of the end of the 75 sleeve beneath said eye being cut away with curved edges leading from said slot, and the portion of the sleeve forming the lower portion of the eye being curved rearwardly to the opening of the eye, said shuttle being 80 formed with vertical and horizontal connecting threading-slots communicating with the slot of the eye-member.

In testimony whereof, I have signed my name to this specification in the presence of 90 two subscribing witnesses.

PATRICK F. HIGGINS.
